UNITED STATES PATENT OFFICE.

CHESTER F. JOHNSON, OF DETROIT, MICHIGAN.

CARBURETOR.

Application filed December 1, 1921. Serial No. 519,132.

To all whom it may concern:

Be it known that I, CHESTER F. JOHNSON, a citizen of the United States, and a resident of Detroit, county of Wayne, and 5 State of Michigan, have invented certain new and useful Improvements in Carburetors, of which the following is a full, clear, concise, and exact description, such as will enable others skilled in the art to which the 10 invention relates to make and use the same, reference being made therein to the accompanying drawings, which form a part of this specification.

The invention relates to carburetors and 15 more particularly to means for maintaining proper relative proportions of fuel and air in the motor mixture under variable operating conditions.

In carburetors of the type in which a jet 20 of fluid fuel is delivered into a mixing chamber by suction, it is generally essential, in order to obtain a proper mixture, that the level of liquid in the reservoir from which the jet is supplied should be approximately constant, in other words, that the 25 delivery nozzle shall be at a predetermined and constant height relative to the level of liquid in the reservoir. This is usually attained by controlling the supply to the reservoir by one of the well-known float valve 30 devices. Under certain conditions, however, the float valve mechanism may be ineffective to maintain accurately a constant level in the reservoir, and the mixture may vary 35 accordingly from the proportions for which the carburetor has been adjusted due to increased tendency of the liquid to flow to the nozzle as the level in the reservoir rises. Such conditions may arise when, for example, 40 the float-actuated valve in the carburetor reservoir acts against a variable pressure, as may occur where the fuel is supplied under a variable head or from a pumping system in which varying pressure may be 45 exerted on the liquid. The height of the liquid level relative to the nozzle may also vary with the inclination of a vehicle upon which the apparatus may be mounted, as, for example, where the nozzle is not centrally located with reference to the bowl or 50 chamber, or where the action of the float itself is not uniform at different inclinations of the apparatus.

The primary object of my invention therefore is the provision of means whereby va-

riations in level in the carburetor supply reservoir, or float chamber, may be automatically compensated so that the quality of the mixture shall not be affected thereby.

A further object is the provision of means 60 responsive to changes in liquid level in the reservoir to reduce the pressure of the atmosphere above the liquid therein as the level rises and permit the pressure to increase as the level falls.

Other objects and advantages will appear 65 from the following description taken in connection with the accompanying drawings, in which—

Fig. 1 is a vertical sectional view showing 70 one embodiment of the invention;

Fig. 2 is a sectional plan view on line 2—2 of Fig. 1;

Fig. 3 is a vertical sectional view showing 75 a modified form;

Fig. 4 is a similar view showing another modified form; and

Fig. 5 is a vertical section showing a detail of the float valve mechanism of Figs. 3 80 or 4.

Figs. 1 and 2 of the drawings illustrate a form of the invention especially designed to compensate for changes in level of liquid adjacent to the fuel nozzle due to variations in inclination of the apparatus such as 85 may occur, for example, when a motor vehicle in which the carburetor is employed is traveling upon inclined road surfaces. In this embodiment 10, 11 indicate respectively upper and lower parts of a carburetor or body which are secured together to enclose between them the mixing chamber 12. The upper portion, 10, is provided with a tubular extension 13 adapted to be connected 90 in any usual or suitable manner to the intake manifold of an internal combustion engine. A throttle valve 14 may be mounted in the extension 13. In the upper face of the body portion 10 is an auxiliary air intake opening 15, the flow of air therethrough being controlled by valve 16 forced 95 toward its seat by spring 17. A pin 18 slidably mounted in the body portion 11 and capable of being adjusted by the elbow lever 19 and adjusting screw 20 provides a 100 support for spring 18 whereby the action thereof may be varied.

In an aperture in the body portion 11 directly below the delivery tube or extension 13 is mounted a downwardly tapering mix-

ing tube 21 the upper part of which extends above the floor of the body 11. Perforations 22 permit condensed fuel which may collect in the body 11 to drain back into 5 the mixing tube.

A receptacle or float bowl 23 which may be formed integrally with the body 11, as shown, or otherwise suitably secured thereto, encloses a fuel chamber 24. A cover 25 10 carries a pipe connection 26 adapted to communicate with a suitable source of supply of liquid fuel. Flow to the fuel chamber 24 is controlled by valve 27 in cooperation with valve seat 28, the valve being actuated toward its seat in the usual manner by float 29. An air vent 30 is provided at a suitable location, as in the cover 25.

The bowl 23 is formed with a cup-shaped portion 31 surrounding the lower end of the 20 mixing tube 21 and with a nozzle 32 centrally located in the cup 31 and extending within the lower end of tube 21. A passage 33 leads to the nozzle from the chamber 24 and serves to deliver fuel to the nozzle under 25 the influence of suction incident to the operation of the engine. It will be noted that the nozzle is located at or near one side of the chamber 24, and that, as a result, any tilting of the float bowl toward or away 30 from the nozzle will vary the level adjacent to the nozzle, or the distance between the delivery orifice of the nozzle and the surface of the liquid in the bowl. Obviously, therefore, a corresponding difference will 35 occur in the stream of liquid drawn into the air current flowing downwardly in cup 31 and upwardly, past the nozzle, into mixing tube 21, the amount of fuel delivered decreasing as the distance through which it 40 must be lifted increases.

In order to compensate for such change in level, I provide means for utilizing the suction in the mixing chamber to decrease the atmospheric pressure on the liquid in 45 the fuel chamber as the level in the latter rises, and vice versa. To this end I provide an opening 34 through the wall of body 11 between the fuel chamber and the mixing chamber, the flow through which is varied 50 by a downwardly tapering valve 35 carried upon rod 36. The lower end of the rod may be slidably supported in a bearing in flange 37 on the wall of bowl 23. A float 38 mounted upon the rod 36 serves to render 55 the position of valve 35 responsive to the level adjacent to the location of the nozzle. If now the apparatus should be tilted so that the level of fuel adjacent to the nozzle rises, the float 38 will also rise, increasing 60 the effective area of the passage 34 and permitting the suction in the mixing chamber 12 to act to an increasing extent upon the fuel in the fuel chamber, or, in other words, to reduce the atmospheric pressure in chamber 24 thus retarding the flow of fuel from 65

the nozzle. A tipping movement in the opposite direction will cause an opposite effect, as will be readily understood.

Referring to Figs. 3, 4 and 5, I have shown therein two embodiments of the invention less liable to variations in level due to tilting, inasmuch as the nozzle is more centrally located with reference to the bowl, but more particularly adapted for use with stationary plants in order to compensate for variations in level due to other causes, such, for example, as those incident to differences in pressure in the fuel line. Referring especially to Figs. 3 and 5, 40 indicates a carburetor body enclosing a mixing chamber 41. An extension 42 is adapted for attachment to the usual manifold and supports a throttle valve 43. An air valve 44 controls the flow of auxiliary air through the intake 45. The bottom of the body 40 is formed with an aperture over which is arranged a diaphragm 46 inclined downwardly at its central portion. A downwardly tapered mixing tube 47 is supported in the central depression of diaphragm 46 and apertures 48 provide for drainage from the mixing chamber. A float bowl 49 encloses the fuel chamber 50 and has a cover 51 suitably secured, as by screws 52, to the body 40. A fuel nozzle tube 53 may be threaded, as at 54, into an aperture in cover 51 and extends within the lower end of mixing tube 47. Openings, as at 55, at the lower end of tube 53 permit fuel to enter the tube from chamber 50, and the lower end of tube 53 may be screw-threaded, as at 56, to receive a screw plug 57 whereby the bowl 49 is clamped to the cover. A float 58 is arranged to operate a valve 59 in the usual manner to control entry of liquid fuel from the supply passage 60. Openings 61 are provided around the periphery of cover 51 to permit entry of air below diaphragm 46, which openings are shielded by the downwardly turned flange 62 on the diaphragm. Air entering the openings 61 passes to the lower end of mixing tube 47 whence it flows upwardly around the nozzle and mixes with the stream of fuel supplied from the nozzle. The usual air vent may be provided, as at 63. Communicating with the fuel chamber 50 both above and below the fuel level therein is the guideway or chamber 64 in which the float 65 is adapted to move vertically in 110 response to changes in level of the liquid in chamber 50. An aperture 66 is formed in the wall between the mixing chamber 41 and fuel chamber 50 providing a passage whereby the suction in chamber 41 may be exerted to reduce the pressure in chamber 50. The flow of air through this passage is controlled by valve 67 mounted upon rod 68 which is carried by float 65. As the level of liquid in chamber 50 rises, therefore, the valve 67 is lifted and the pressure upon the 115

liquid in chamber 50 is correspondingly reduced thereby compensating for the effect upon the flow from nozzle 53 due to the higher level of liquid.

5 The form shown in Fig. 4 varies from that of Fig. 3 in that the passage providing for communication between the mixing chamber and the fuel chamber consists of a channel 70 opening through a transverse passage to the mixing chamber at 71 and to the exterior atmosphere at 72. The flow of air into the transverse passage through the port 72 is controlled by a valve member 73 mounted upon the upper end of the 15 rod 68' carried by floats 65. In the operation of this form of the apparatus the effect of suction in the mixing chamber in reducing the pressure in the fuel chamber will be increased as the port 72 is closed and lessened as the port is opened. The pressure on the liquid in the fuel chamber is therefore varied in response to changes in level therein as in the forms previously described.

20 While in the foregoing description I have referred specifically to the control of flow of the liquid fuel by varying the atmospheric pressure upon the surface of the fuel, it will be understood that such control may be effected by any desired form of oburating or flow controlling means acting directly or otherwise to counteract the increased tendency of the fuel to flow toward the mixing chamber due to rise of level in the supply chamber, and it will be appreciated that the invention will include within its scope all such variations and modifications covered by the language of the appended claims and adapted to perform the function specified. Furthermore, in embodiments 25 of the invention wherein provision is made for automatic variation of the atmospheric pressure within the fuel chamber, it will be obvious that such variation may be effected otherwise than by connection to the mixing chamber, hence I do not desire to be limited, in the broader aspects of the invention, to the utilization of sub-atmospheric pressure or connection to the mixing chamber only.

30 This application is designed as a substitute for my application Serial No. 74,754, filed January 28, 1916, and is a continuation thereof insofar as the two applications include common subject matter.

I claim:

35 1. In a carburetor, in combination, a vented fuel chamber, means for regulating the flow of fuel thereto, a mixing chamber, said fuel chamber arranged to supply fuel to said mixing chamber, a passage connecting said chambers, and means actuated by the liquid in said fuel chamber for controlling flow through said passage to apply suction increasingly to said fuel chamber as the fuel therein rises.

40 2. In a carburetor, the combination of a

float chamber, a mixing chamber, means for delivering fluid fuel from said float chamber to said mixing chamber, and valve means adapted to be actuated by the fuel in said float chamber and operative to cause an increasing retardation in the flow of fuel from said float chamber to said mixing chamber as the level of fuel in said float chamber rises.

45 3. In a carburetor, the combination of a fuel chamber, means for regulating the flow of fuel thereto, a mixing chamber, a fuel nozzle feeding fuel thereto, means for supplying air to said mixing chamber, said fuel chamber and said mixing chamber being provided with a connecting air passage, and a float valve for regulating the action of the suction of said mixing chamber on the surface of the fuel of the said fuel chamber through said passage.

50 4. A carburetor comprising a nozzle subject to suction, a fuel chamber subject to suction from the same source as that for the nozzle for supplying fuel to said nozzle, and means responsive to the level of fuel in said chamber tending to increase the absolute pressure in said chamber upon decrease of the fuel level therein and vice versa, to thereby tend to maintain the quality of the mixture constant throughout variations in the level of fuel in said chamber.

55 5. In combination, a mixing chamber, a float chamber adapted to supply liquid fuel to said mixing chamber, a passage connecting the mixing chamber and the upper portion of the float chamber, and means operable to vary the pressure in said float chamber by varying the suction exerted through said passage to automatically lower the pressure on the liquid in said float chamber as the fuel therein rises.

60 6. In a carburetor, a mixing chamber, a nozzle arranged to supply fluid fuel to said mixing chamber, a fuel chamber adapted to feed fuel to said nozzle, and means responsive to the level of fuel in said fuel chamber operative to counteract the increased tendency of fuel to flow to said nozzle due to rise of said level.

65 7. In combination, a mixing chamber, a fuel chamber, float controlled means for supplying liquid fuel thereto, a nozzle for feeding liquid fuel from said fuel chamber to said mixing chamber, said nozzle so positioned that the liquid adjacent thereto in said fuel chamber is subject to variations in level with variations in inclination of said parts, and means for reducing the atmospheric pressure in said fuel chamber in accordance with the rise in said level.

80 8. In combination, a mixing chamber, a fuel chamber, float controlled means for supplying liquid fuel thereto, a nozzle for feeding liquid fuel from said fuel chamber to said mixing chamber, said nozzle so posi-

tioned that the liquid adjacent thereto in said fuel chamber is subject to variations in level with variations in inclination of said parts, and means for reducing the atmospheric pressure in said fuel chamber in accordance with the rise in said level, said means comprising a passage between said

chambers, a valve adapted to vary the area of said passage, and a float responsive to level in said fuel chamber and adapted to 10 actuate said valve.

In testimony whereof I affix my signature.

CHESTER F. JOHNSON.
